Inventor,

W. R. McComas.

UNITED STATES PATENT OFFICE.

WILLIAM R. McCOMAS, OF OAKLEY, ASSIGNOR TO CRANE, BREED & CO., OF CINCINNATI, OHIO.

DESIGN FOR A COFFIN-HANDLE.

SPECIFICATION forming part of Design No. 12,126, dated January 18, 1881.

Application filed November 18, 1880. Term of patent 7 years.

To all whom it may concern:

Be it known that I, Wm. R. McCOMAS, of Oakley, in the county of Hamilton and State of Ohio, have originated a new Design for 5 Coffin-Handles, of which the following is a full, clear, and exact description, reference being had to the concomitant drawing, making part of this specification.

My invention consists of a design for a new 10 knuckle-joint handle for coffins or caskets, the same being circular in form, with a symmetrical serrated palmate leaf, G, extending from the center upward on the prime vertical line, concealing one-third part of the ornamented base 15 II. The lower part is formed by symmetrical lobate leaves D, lying below and outside of the circular band, divided by a trefoil scroll or stem extending upward on the prime vertical line, until inclosed by a pointed arch supporting the 20 knuckle. Crochets extend upward along the outside edge of the circular band or border

from the leaves forming the bottom, ending underneath the top ornament, G.

The ornamentation consists of a V-shaped ornament, A, encircling the knuckle, B, this 25 inclosed by a vine-stem, C, with conventional incised leaves, which are again inclosed by a band or border ornamented with small hemispheres. The lower part is ornamented with lobate leaves D lying outside of the circular 30 band E, and divided by a trefoil scroll on stem F. The whole is finished by crochets and balls extending from leaves D and running underneath the top ornament, G.

What I claim as new, and desire to secure 35 by Letters Patent, is—

The design of a socket or ear of a coffin-handle, as shown and described.

WM. R. McCOMAS.
